COMBINED CLOCKFACE AND HANDS

Dominick A. Giordano, Philadelphia, Pa., assignor of a fractional part interest to The Raymond Lee Organization, New York, N.Y.

Filed July 19, 1971, Ser. No. 164,187

Term of patent 14 years

Int. Cl. D10—07

U.S. Cl. D42—1 B

The figure is a front elevational view of a combined clockface and hands, conventionally of non-appreciable thickness, showing my new design.

I claim:

The ornamental design for a combined clockface and hands, as shown and described.
